UNITED STATES PATENT OFFICE.

NICKOLAS F. EGLER, OF CHICAGO, ILLINOIS.

FURNACE USED IN CONNECTION WITH THE MAKING OF STEEL.

Application filed January 20, 1922. Serial No. 530,522.

To all whom it may concern:

Be it known that I, NICKOLAS F. EGLER, a citizen of the United States, residing in Chicago, in the county of Cook and State 5 of Illinois, have invented certain new and useful Improvements in Furnaces Used in Connection with the Making of Steel.

More particularly the type of furnace with which my invention is concerned is of 10 the reversing blow torch open hearth type. In these furnaces the inlet port has been centrally located and the auxiliary or, outlet ports have been placed to the side or in front of the inlet ports through which former, of course, the fuel is supplied into the 15 hearth.

In connection with furnaces of this construction, difficulty has been experienced in maintaining the inlet ports repaired because 20 of the central location of the inlet ports, inasmuch as there is a constant bombardment of the ports by the gases and by the particles carried over by the gases, and inasmuch as these particles have considerable 25 inertia at the time they impinge against the central port. Also in open hearth furnaces of large capacity a single inlet port concentrates the zone of maximum heat so that the charge near the inlet end of the 30 furnace is not melted as uniformly as might be desired. One objection is that the heat from a centralized port is confined to the center and cuts a channel in front of the port. To avoid this I have provided two 35 inlet ports on each end of the furnace about a centrally located outlet port so as to distribute the heat more generally and uniformly across the bath. This twin or multiple inlet port arrangement furthermore 40 avoids the bombardment mentioned.

In this twin inlet port construction it is desirable to direct the ports towards the central outlet port in the opposite head of the furnace, not only to decrease the cutting 45 effect of the outgoing gases on the inlet port but also to protect the front and back walls of the furnace against the impingement that would otherwise result when the flame flares in front of the inlet ports. It will be understood that it is much more important to 50 maintain the shape of the inlet ports than of the outlet ports as it is important to stabilize combustion conditions, which conditions are varied by variations in the inlet

ports. The conditions of combustion not 55 being so sensitive to the condition of the outlet port, the advantage of centrally locating the outlet and of disposing the inlet ports about the outlet will be readily appreciated. 60

Among the objects of my invention are:— To provide a centrally located port for use exclusively as an outlet;

To provide combined fuel and air ports 65 on either side of the outlet;

To provide combined fuel and air ports on one end of the furnace, converging toward the outlet port at the opposite end of the furnace; and

To provide other details of improvement 70 tending to increase the efficiency and serviceability of a furnace of the above character.

To accomplish the foregoing and other useful ends, my invention comprises means 75 hereinafter more fully set forth and claimed.

Referring to the accompanying drawings:—

Fig. 1 is a top sectional view, the section being taken along the line, 1—1, Fig. 2. 80

Fig. 2 is a section in elevation taken along the line, 2—2, Fig. 1.

Fig. 3 is a section in elevation taken along the line, 3—3, Fig. 1.

Referring to the drawings by characters 85 of reference, 2 and 3 represent the main air and gas inlet flues respectively, which extend transversely across one head of the open hearth furnace. A passage 4 extends upward from the flue 2, and a passage 90 5 extends upward from the flue 3, the passages being at one side of the head. Similar passages 10 and 14 extend upwardly from the flues 2 and 3 respectively, at the other side of the head. A port 6, having an outlet orifice 7, extends longitudinally above the passages 4 and 5, and a similar port 9 having an outlet orifice 8 extends longitudinally above the passages 10 and 14. The ports are inclined toward each other 95 at their outlet ends and form open chambers into which the air and gas from the flues are mixed and then fed into the hearth. The opposite head of the furnace is constructed in a similar manner, the ports 100 having orifices 16 and 17 through which the air and gas mixed therein is fed into the hearth. 105

Referring to Fig. 3, it will be seen that I provide a passageway 11 which extends upwardly from the main air flue 2, intermediate the passages 4 and 10. A horizontal chamber 13 extends longitudinally above the passageway 11, intermediate the ports 6 and 9, and opens into the hearth. The chamber is slightly larger in diameter than the end of the passageway which is 5 in open communication therewith, and a valve 12 is provided in the chamber to close the end of the passageway 11. A valve rod extends through the top wall of the furnace, is secured to the valve and can be operated 10 by any well known suitable means. A similar passageway and chamber are provided at the opposite head of the furnace, and a valve 18, similar to valve 12, is positioned therewith and operated in a similar 15 manner.

When the ports at the right hand side of the furnace are functioning to feed fuel into the furnace, the valve 12 is placed in position to close the passageway 11 joining 20 the chamber 13, and the valve 18 is raised, whereby the products of combustion will pass into the chamber 15 and down the passageway thereunder into the main air flue 2, and thence into the air checker. 25 When the left hand side of the furnace is functioning to feed fuel to the furnace, the valve 18 will close the passageway 11, and the valve 12 in the opposite head of the furnace is opened, the products of combustion 30 passing into the chamber 13 and down the passageway 11 into the main air flue 2, thence to the air checker. In a similar manner the gases of combustion will also 35 pass into the orifices 7 and 8 through the ports 6 and 9 and down the passageways 40 5 and 14 into the main gas flue 3, and then to the gas chamber, and also down through the passages 4 and 10, into the flue 2 and then to the air checker. The similar ports 45 and passages function in a similar manner at the opposite side when the fuel is fed from the right hand head.

With respect to the connecting passage 50 between the orifices 7 and 8, and the main gas conduit 3, the construction is similar to the construction shown in Fig. 3 except that there is no passageway corresponding to the passageway 11.

It will be observed that the ports 6 and 55 9, are arranged at an angle inclined toward each other at their orifices and pointing in substantially the same direction toward the chamber 15; likewise ports 16 and 17 are pointing toward the chamber 13. This 60 arrangement directs the gases from the inlet orifice at one side to the chamber into the orifices at the opposite side for the purpose already described, and concentrates the flame at a desired point within the 65 furnace. It will be understood, of course,

that the construction of the furnace on either side is a duplication of the opposite side.

Referring to the drawing, it will be observed that each inlet port has a longitudinal axis parallel with the general direction of the flow of the gases. It will be seen, therefore, that a vertical plane may be erected containing the longitudinal axis of both outlet chambers and that this vertical plane also contains the longitudinal axis of the furnace. Furthermore, as shown in the drawing, the inlet ports which are disposed about the outlet chambers are preferably disposed converging toward this vertical plane. In other words, the longitudinal axes of the inlet ports in the preferred arrangement, converge toward the said vertical plane. Therefore, rather than have the longitudinal axes of the inlet ports 75 extending parallel to the vertical plane, I have arranged to converge these axes toward the vertical plane with the desired results already described.

Although in the drawing I have shown only a pair of inlet ports in each head, it will be understood that I contemplate using, if necessary, more than two such ports, in other words, I contemplate the use of a plurality of inlet ports disposed about the 80 outlet chambers.

What I claim as my invention is:—

1. In an open hearth furnace, a pair of converging ports each for supplying both fuel and air, and both connected to supply 100 fuel and air simultaneously in substantially the same direction to the hearth.

2. In an open hearth furnace, a pair of inlet ports at one head of the furnace, each for supplying the bath with fuel and air, 105 and an outlet port in said head located between said ports.

3. In an open hearth furnace of the reversible type having the two opposite heads or vertical walls facing each other, a horizontal chamber in each head serving as an outlet exclusively, each of said chambers having its longitudinal axis in a vertical plane passing through the longitudinal axis 110 of the hearth.

4. In an open hearth furnace of the reversible type having the two opposite heads or vertical walls facing each other, a chamber in each head serving as an outlet exclusively, each of said chambers having its longitudinal axis in a vertical plane, said plane containing also the longitudinal axis of the hearth, and a fuel chamber on each side of the outlet port.

5. In an open hearth furnace of the reversible type having the two opposite heads or vertical walls facing each other, a chamber in each head serving as an outlet exclusively, each of said chambers having its longitudinal axis in a vertical plane, said plane 125 130

- containing also the longitudinal axis of the hearth, and an inlet chamber on each side of the outlet port, the inlet ports on one head converging toward the outlet chamber of the opposite head.
6. In a furnace, a chamber with its longitudinal axis horizontally disposed, said chamber for use as an outlet exclusively, the longitudinal axis of the chamber and of the hearth located in the same vertical plane to feed mixed air and gas in substantially the same direction to the hearth, and inlet ports disposed on either side of said plane.
7. In a furnace, a chamber with its longitudinal axis horizontally disposed, said chamber providing an outlet exclusively, the longitudinal axes of the chamber and of the hearth being located in the same vertical plane, and an intake port located on each side of said plane to feed mixed air and gas in substantially the same direction to the hearth, the longitudinal axes of said intake ports converging toward said plane.
8. In a furnace, a chamber for use as an outlet exclusively, and an inlet port on either side of a vertical plane through the longitudinal axis of said outlet chamber to feed mixed air and gas in substantially the same direction to the hearth, said inlet ports converging toward said plane.
9. In an open hearth furnace, a head having intake ports and an outlet chamber intermediate the ports, the longitudinal axes of the ports and chamber being disposed at an angle to the vertical axis of said head and in open communication with the hearth, the inlet ports being connected to supply fuel in substantially the same direction to the hearth.
10. In an open hearth furnace of the reversible type having two opposite heads facing each other, each of said heads having a plurality of fuel feeding ports and an outlet chamber intermediate the ports, and a valve within each chamber, said ports directing fuel from either head into the hearth while the ports and chamber in the opposite head carry off the products of combustion.
11. In an open hearth furnace of the reversible type having two opposite heads facing each other, each of said heads having therein a plurality of horizontally extending fuel feeding ports, a horizontally extending outlet chamber intermediate the ports, transversely extending air and gas flues, and a passageway extending between the air flue and the outlet chamber.
12. In an open hearth furnace of the reversible type having two opposite heads facing each other, each of said heads having therein a plurality of horizontally extending fuel feeding ports, a horizontally extending outlet chamber intermediate the ports, transversely extending air and gas flues, upwardly extending passages between each port and the flues, a passageway extending between the air flue and the outlet chamber, and a valve in each outlet chamber to open or close the passageway.
13. In an open hearth furnace of the reversible type having two opposite heads facing each other, each of said heads having therein a plurality of horizontally extending fuel feeding ports, a horizontally extending outlet chamber intermediate the ports, transversely extending air and gas flues, upwardly extending passages between each port and the flues, and a passageway extending between the air flue and the outlet chamber intermediate the air passages.

In witness whereof I have hereunto signed my name, this 28th day of December, 1921

NICKOLAS F. EGLER.
